DATA-REVEALING DEVICE

Isidore Goldner, Brooklyn, N. Y.

Application October 10, 1939, Serial No. 298,744

10 Claims. (Cl. 273—161)

This invention relates to a structurally and functionally improved data-revealing device which may function as a puzzle in order to reveal—in the hands of the initiated—information which will be bewildering and inexplicable to the uninitiated.

While the present invention may be employed in numerous different associations and in order to simultaneously furnish a variety of information such as, the age, height, and weight of a certain person, the age of the inquirer, and the ages of his two parents, the two or three initials of the given and last names of any person, etc., it will be of particular utility when employed to give information such as the month, day of the month, and year of a birth or other event.

It is an object to furnish a unit of this character which may thus be employed for numerous different purposes but which in all of its embodiments will embrace a relatively compact set of individual elements or cards capable of manufacture at a nominal figure so that the unit may, for example, have associated with it advertising data and be given away or, if desired, may be sold for amusement and entertainment purposes.

A further object is that of furnishing a device of this type which will require no special skill for its manipulation so long as the person employing the same is initiated in its use; which comprises among others the exhibiting of cards bearing certain portions of the various data to be correlated and having the spectator indicate whether or not each card so presented does or does not contain data which comprises in part the total information which is to be assembled. It is only necessary that the person operating the puzzle obtain a "yes" or "no" answer from the spectator and it is apparent that the results achieved by such person will be extremely mystifying to those persons who are not familiar with the manner in which the unit functions.

Another object is that of constructing a data-revealing device embracing several elements and in which such elements when properly associated with each other will—as afore brought out—simultaneously reveal a multiplicity of data rather than a single item.

Still another object is that of providing a unit the several parts of which do not have to be arranged in any predetermined or carefully maintained sequence and in fact these parts will individually appear to be so diverse with respect to their individual components that even a care-

ful observer will be unable to fathom how the ultimate results are achieved.

With these and other objects in mind, reference is had to the attached sheets of drawings illustrating one practical embodiment of the invention and in which:

Fig. 1 illustrates in fragmentary form certain of the cards or elements which may form a part of the complete device or unit;

Fig. 2 is a perspective view of the envelope 10 which is to receive these cards or elements;

Fig. 3 is a similar view of such elements in association with the envelope or receiver; and

Fig. 4 is a face view of a "master" card such as would be employed in connection with a complete set of elements or cards.

As afore brought out, the present device is not limited in connection with revealing information as to the day, month, and year of a given event, although it is likely that a large percentage of units constructed in accordance with the teachings of this invention will primarily have in mind the providing of such data. Thus, in the annexed drawings and following description a device has been shown and described which primarily seeks to provide such particular information. Such illustration and description are accordingly to be taken in illustrative rather than in a limiting sense. Likewise, in Figs. 1 to 3 only a portion of a complete set has been illustrated with a view to avoiding unnecessary and in some respects a confusing illustration; it being hereinafter apparent to those skilled in the art, precisely the manner in which additional elements are to be constructed in order to provide such a complete set.

Thus, referring to Fig. 1, the numerals 5 to 10 inclusive indicate a series of cards, the first and third of which show the years 1900, 1902, and 1903 respectively. The second and sixth cards show the numerals 1, 3, and 4, respectively, and the fourth and fifth cards bear the designations of the months January, March and April. It is to be understood that each one of these cards bears upon its front and rear faces similar data and each of the cards preferably has an upper or heading space or area 11 which may receive advertising or other desired data. If such data is not desired, this space may be materially reduced or embody any desired configuration.

Likewise each of the cards is formed with a series of apertures 12 which to even a discerning eye appear to be arranged in no particular sequence or order. However, as indicated by the reference numeral 13, each of the cards will have

upon one of its faces a secret mark or indication. This may take any desired form and present an innocuous appearance such as would be the case if in small type there appeared on predetermined faces of the cards the legend "Mfg. USA."

A "master" card may be conveniently furnished by having the same form a part of an envelope 14 as indicated in Fig. 2. If such a construction 10 is resorted to, the forward face of the envelope is provided with a series of windows or apertures 15, one for each of the possible indications of data which might occur. The face of the latter card is furnished in the illustrated embodiment 15 by the rear wall 16 of the envelope and this rear wall is furnished, by imprinting or otherwise, with indicia, corresponding element for element with all of the indicia which may be embraced in, or capable of being revealed by a given device embodying the present invention. As is also 20 apparent, both the cards and the envelope and/or "master" card may be formed of any desired material or materials.

The present invention depends upon the splitting or dividing process which produces the desired data by means of the "two" system. In other words, all numbers are represented as the sum of the powers of two instead of by means of the decimal or "ten" system which represents all 25 numbers as a sum of the powers of ten. Thus, referring to Fig. 4 wherein a "master" card has been illustrated which is to be furnished in connection with a system to determine a given day, month, and year, it will be observed that 103 divisions are presently provided by an aggregation of abbreviations 16 designating months, symbols 17 designating years, and numerals 18 designating individual days. This card will furnish an answer within the above limits from the 30 years 1867 to 1930 inclusive. This amounts to 64 years to which is added 12 months making a total of 76 and there are additionally provided 32 spaces for individual numbers such as 13. The reason for employing 32 numerals is that 35 of course 31 numbers are necessary to represent the possible number of days in a month. However, up to the number 32 is present in order that such numbers may be split by 2 five times successively and in equal parts, i. e., 16, 8, 4, 2, and 40 1. In connection with the 64 years, it is necessary to split these 6 times in succession to arrive at a single definite year, while in connection with the months 4 operations which split 16 numbers successively into equal parts are necessary in order to arrive at a given single designation. Thus, we have a total of 15 splitting operations in order to arrive at a single given year, month, and day. Accordingly, in addition to the 45 "master" card the particular set will include 15 cards, each one of which will be formed with sight apertures arranged in a manner such that a definite splitting function is achieved.

At the same time it will be understood that it 50 will not be necessary to arrange these cards in any particular sequence. All that will be necessary will be to display the set of cards one after another to the person being interrogated. In the event that the answer to questions propounded shows that a given year, day or month 55 appears upon a particular card being displayed, that card will be arranged with the secret mark 13 uppermost. If the answer is in the negative, this front face of the card will be disposed downwardly. In this connection it is pointed out that 60 as the cards are stacked or assembled, each of

the cards pertaining to data outside their particular sphere have non-interfering sight apertures through which the data of other cards may be viewed. For example, the year cards have non-interfering sight apertures for each of the 5 days and months appearing on the "master" card, while the month cards have non-interfering sight apertures for each of the days and years appearing on the "master," and the day cards have non-interfering sight apertures for 10 each of the months and years appearing on the "master" card. It will thus be apparent that upon all cards having been properly stacked one upon the other and arranged upon the "master," the desired answer will be displayed by the non- 15 obscured portion of the latter.

This has been shown in simple fashion in Figs. 1, 2, and 3 in which the ultimate answer desired is January 3, 1903. The critical apertures have been indicated in dash lines in Figs. 1 and 20 2 and it will be seen that by facing the cards as shown in Fig. 1, those portions of the "master" card or back 16 which are not to be obscured by portions of one or more cards will in each instance fall in line with the apertures appearing 25 on all cards. Accordingly as shown in Fig. 3 the desired result is displayed through the apertures 15 of the envelope. It will be borne in mind that the only thing the operator or demonstrator will have to be sure of is the facing 30 of the cards inwardly or outwardly. This may be done in a very casual manner and without, as is ordinarily necessary, having the upper edges of certain cards extend upwardly while others are arranged to extend downwardly. Aside from 35 the elimination of this step which is apparent to even a casual observer, it is nevertheless apparent that by means of the present invention a number of answers are simultaneously given rather than having the device limited to a single 40 answer. Of course, if a greater or lesser amount of questions are to be simultaneously answered, the set of cards may be correspondingly increased or diminished in number.

To recapitulate and again review the construction and operation of the device in order 45 that despite the elimination of unnecessary illustration the detailed construction of each card may be grasped, it is apparent that each card either in its positive or negative position leaves exposed to view exactly one-half of the data 50 which is printed on the "master" card and at the same time covers the other half of the data upon such "master" card. The function of exposing and covering data is accomplished by 55 perforating the card and leaving unperforated the "mate" of this perforation. "Mate" refers to an identical area on the same side of the card either to the right or to the left of the perforation through a horizontal line on the face of the 60 card. Thus, one perforation or opening and one area, unperforated, both equi-distant from the respective left and right edges of a given card, produce splitting of data.

As afore brought out this is accomplished by 65 placing a card bearing these perforations and unperforated areas in proper registry with the top of the "master" card. The openings on each card present a confusing appearance to the eye. The openings applicable to each card are widely 70 scattered and interspersed with other openings which function in connection with cards bearing other data. In other words, if a given card refers to a year certain of the openings or apertures of that card are provided for the purpose 75

of leaving unobscured the indicia designating, for example, days and months. Also, it will be understood that the "master" card will require no manipulation excepting only that the other cards will be superimposed thereon.

From the foregoing the construction of the apertured cards associated with the "master" card of Fig. 4 may readily be visualized. For example: in connection with the cards bearing the year indicia, the first will obscure thirty-two of the year designations appearing upon the card as shown in Fig. 4. The next card will cancel half of the remaining year imprints; leaving unobscured sixteen yearly designations. Application of the next apertured card will, in turn, cancel half of these and the next card will divide the remainder in half; thus leaving four yearly indicia uncovered. Obviously, through application of two more cards, of this type, all will be obscured except the date of one year, which will be the one desired. The cards dealing with, for example, the days of the month and months of the year will be apertured to achieve the same functional results with respect to the indicia relating to their respective categories. It is thus apparent that there is no useful purpose in illustrating in detail the set of cards for association with the "master" shown in Fig. 4. The precise construction of these will follow the structure and principles generally indicated in Fig. 1.

From the foregoing it will be understood that among others the several objects of the invention as specifically afore noted are achieved. Obviously numerous changes in construction and rearrangement of the parts might be resorted to in order to provide for any desired type of answer or answer and without departing from the spirit of the claims.

I claim:

1. A data-revealing device including in combination, a "master" card, at least a first set and a second set of different indicia upon the face thereof, a first and second set of further cards, the individual cards of each set being adapted to be superimposed upon said "master" card, indicia formed on cards of the first set corresponding to some of the indicia of the first set on the "master" card, indicia formed on the cards of the second set corresponding to some of the indicia of the second set on the "master" card, means associated with the individual cards of the first set to reveal only a portion of the related indicia of the first set on the "master" card and all of the indicia of the second set on the "master" card, and means associated with the individual cards of the second set to reveal only a portion of the related indicia of the second set on the "master" card and all of the indicia of the first set on the "master" card, whereby predetermined data on said "master" card will be displayed through the individual cards.

2. A data-revealing device including in combination, a "master" card, at least a first set and a second set of different indicia upon the face thereof and extending in the same direction and being decipherable from one given position, a first and second set of further cards, the individual cards of each set being adapted to be superimposed upon said "master" card, indicia formed on the cards of the first set corresponding to some of the indicia of the first set on the "master" card, indicia formed on the cards of the second set corresponding to some of the indicia of the second set on the "master" card, means associated with the individual cards of the first set to reveal only a portion of the related indicia of the first set on the "master" card and all of the indicia of the second set on the "master" card, and means associated with the individual cards of the second set to reveal only a portion of the related indicia of the second set on the "master" card and all of the indicia of the first set on the "master" card.

ciated with the individual cards of the first set to reveal only a portion of the related indicia of the first set on the "master" card and all of the indicia of the second set on the "master" card, and means associated with the individual cards of the second set to reveal only a portion of the related indicia of the second set on the "master" card and all of the indicia of the first set on the "master" card, whereby predetermined data on said "master" card will be displayed through the individual cards.

3. A data-revealing device including in combination, a "master" card, at least a first set and a second set of different indicia upon the face thereof, a first and second set of further cards, the individual cards of each set being adapted to be superimposed upon said "master" card, indicia formed on the cards of the first set corresponding to some of the indicia of the first set on the "master" card, indicia formed on the cards of the second set corresponding to some of the indicia of the second set on the "master" card, apertures associated with individual cards of the first set to reveal only a portion of the related indicia of the first set on the "master" card and all of the indicia of the second set on the "master" card, and apertures associated with individual cards of the second set to reveal only a portion of the related indicia of the second set on the "master" card and all of the indicia of the first set on the "master" card, whereby predetermined data on said "master" card will be displayed through the individual cards.

4. A data-revealing device including in combination, a "master" card, at least a first set and a second set of different indicia upon the face thereof, extending in the same direction and being decipherable from one given position, a first and second set of further cards, the individual cards of each set being adapted to be superimposed upon said "master" card, indicia formed on the cards of the first set corresponding to some of the indicia of the first set on the "master" card, indicia formed on the cards of the second set corresponding to some of the indicia of the second set on the "master" card, apertures associated with the individual cards of the first set to reveal only a portion of the related indicia of the first set on the "master" card and all of the indicia of the second set on the "master" card, and apertures associated with the individual cards of the second set to reveal only a portion of the related indicia of the second set on the "master" card and all of the indicia of the first set on the "master" card, whereby predetermined data on said "master" card will be displayed through the individual cards.

5. A data-revealing device including in combination, a "master" card, at least a first set and a second set of different indicia upon the face thereof, a first and second set of further cards, the individual cards of each set being adapted to be superimposed upon said "master" card, identical indicia formed on each of the cards of the first set on each of its faces and corresponding to some of the indicia of the first set on the "master" card, identical indicia formed on each of the cards of the second set on each of its faces and corresponding to some of the indicia of the second set on the "master" card, means associated with the individual cards of the first set to reveal only a portion of the related indicia of the first set on the "master" card and all of the indicia of the second set on the "master" card, and means associated with the individual cards of the second set to reveal only a portion of the related indicia of the second set on the "master" card and all of the indicia of the first set on the "master" card.

the second set to reveal only a portion of the related indicia of the second set on the "master" card and all of the indicia of the first set on the "master" card, whereby predetermined data on said "master" card will be displayed through the individual cards.

6. A data-revealing device including in combination, a "master" card, at least a first set and a second set of different indicia upon the face thereof, a first and second set of further cards, the individual cards of each set being adapted to be superimposed upon said "master" card, identical indicia formed on the individual cards of the first set on each of its faces corresponding to some of the indicia of the first set on the "master" card, identical indicia formed on the individual cards of the second set on each of its faces corresponding to some of the indicia of the second set on the "master" card, means associated with the individual cards of the first set to reveal only a portion of the related indicia of the first set on the "master" card and all of the indicia of the second set on the "master" card, means associated with the individual cards of the second set to reveal only a portion of the related indicia of the second set on the "master" card and all of the indicia of the first set on the "master" card, and an inconspicuous mark associated with one only of the faces of said individual cards to identify the manner in which each of said individual cards is to be arranged upon said "master" card, whereby predetermined data on said "master" card will be displayed through the individual cards.

7. A data-revealing device including in combination, a "master" card, at least a first set and a second set of different indicia upon the face thereof and extending in the same direction and being decipherable from one given position, a first and second set of further cards, the individual cards of each set being adapted to be superimposed upon said "master" card, identical indicia formed on the individual cards of the first set on each of its faces corresponding to some of the indicia of the first set on the "master" card, identical indicia formed on the individual cards of the second set on each of its faces corresponding to some of the indicia of the second set on the "master" card, apertures carried by the individual cards of the first set to reveal only a portion of the related indicia of the first set on the "master" card and all of the indicia of the second set on the "master" card, apertures carried by the individual cards of the second set to reveal only a portion of the related indicia of the second set on the "master" card and all of the indicia of the first set on the "master" card, and an inconspicuous mark associated with one only of the faces of said individual cards to identify the manner in which each of said individual cards is to be arranged upon said "master" card, whereby predetermined data on said "master"

card will be displayed through the individual cards.

8. A data-revealing device including in combination, an envelope, a "master" card formed on the inner rear wall thereof, at least a first set and a second set of different indicia formed on the face of said "master" card, a first and second set of further cards, the individual cards of each set being adapted to be superimposed upon said "master" card, indicia formed on the cards of the first set corresponding to some of the indicia of the first set on the "master" card, indicia formed on the cards of the second set corresponding to some of the indicia of the second set on the "master" card, means carried by the individual cards of the first set to reveal only a portion of the related indicia of the first set on the "master" card and all of the indicia of the second set on the "master" card, means carried by the individual cards of the second set to reveal only a portion of the related indicia of the second set on the "master" card and all of the indicia of the first set on the "master" card, and said envelope having means in its upper face to display data whereby predetermined data on said "master" card will be displayed through the individual cards and the upper face of the envelope.

9. A data-revealing device including in combination, a "master" card having upon its face a set of indicia extending in the same direction and being decipherable from one given position, a set of cards, the individual cards of said set being adapted to be superimposed upon said "master" card, identical indicia on each of the faces of each individual card and corresponding to some of the indicia on the "master" card, and means on each individual card to reveal only a portion of the indicia on the "master" card, whereby predetermined data on said "master" card will be displayed through the individual cards.

10. A data-revealing device including in combination, a "master" card, a set of indicia formed upon the face thereof and extending in the same direction and being decipherable from one given position, a set of further cards, the individual cards of said set being adapted to be superimposed upon said "master" card, identical indicia formed on each individual card on each of its faces corresponding to some of the indicia on the "master" card, and apertures carried by each individual card to reveal only a portion of the indicia on the "master" card, the apertures in each of said cards being arranged so that any given card is perforated in one area and left unperforated in a corresponding area through a horizontal line in the face of such card, whereby predetermined data will be displayed through the individual cards.

ISIDORE GOLDNER.
